UNITED STATES PATENT OFFICE.

ISAAC A. BAUM, OF CHICAGO, ILLINOIS.

METAL FRAME AND SUPPORT THEREOF.

Application filed May 5, 1928. Serial No. 275,433.

My invention relates to framing for wall openings and particularly to an improvement on or addition to the structure disclosed and claimed in my co-pending application

5 Serial No. 248,156, filed January 20, 1928.

In the structure of my said co-pending application, I disclosed means for facilitating the joining of the vertical and transverse members of a metal frame by the use 10 of a wood block held at the intersection, and nails or other fastening devices extending through the overlapping portions of the metal frame members at their junctions and being seated in the wood block. The invention here disclosed relates to a similar construction but in which the wood block is extended vertically and serves as a convenient means for bracing or holding the metal frame in proper position prior to the 15 laying or finishing of the wall within which the frame is mounted.

While metal frames corresponding to rough bucks are desirable from many angles yet the means for mounting or holding the 20 frame in its initial position before the wall is laid has required considerable time and material that has offset somewhat the economy in the use of metal bucks. In the construction here disclosed the matter of installation is extremely simple. The respective vertical and horizontal members of the frame are constructed in the shop and shipped separately to the job. They are 25 there assembled on the floor with long blocks 30 extending upwardly from the junctions of members and the long wood members are nailed to the ceiling after the parts have been properly aligned. In tile wall construction the wood members are sawed off at the upper 35 limits of the frame after the masonry has reached a point near the top of the frame. In wood frame construction the wood members are left in place and act as a support for wall elements.

40 My invention will be more readily understood by reference to the accompanying drawing, in which—

Fig. 1 is a side elevation of a frame structure arranged in accordance with my invention;

50 Fig. 2 is a large sectional elevation of a corner thereof, and

Fig. 3 is a sectional view of the line 3—3 of Fig. 2.

55 In the drawing, I have illustrated a frame member consisting of vertical element A,

and a horizontal element B, both of which are of generally channel shape, as best shown in Fig. 3. At its ends the element B is provided with angle shaped plates 10, 60 one leg of the angle of which is welded to a side flange of the element B while the other leg of the plate overlaps a side flange of the element A. Registering holes are provided in the overlapping metal 65 elements and nails 11 are passed through the holes and into a wood member 12 which may be in the form of a 2 x 4. Holes at other points in the side flange of the frame member A provide for nails 13 that serve as 70 independent holding means for the wood and metal members. Preferably an abutment or shelf 14 is mounted on the inside of the channel member A, by riveting or welding, and the lower end of the 2 x 4 rests thereon. The 75 wood member extends upwardly to a point in contact with or adjacent to a ceiling 15 and after the parts are positioned the wood member is nailed either to a block 16 or toenailed to the ceiling.

If the wall is of tile or masonry construction the wood members will be sawed off at the dotted line 17 when the masonry has reached a point near the top of the frame. Or, if desired, a hole 17a may be made in the 80 wood member at a point beneath the web of the element B, and a keyhole saw may be used for cutting off the wood member so that it will not interfere with the tile. If the wall is to be of wood or composite construction the wood elements are left in place 85 and additional wood elements are installed as indicated in dotted lines in Fig. 1. These wood elements comprise a horizontal member 18 that lies on the web of the element B 90 and is held by means of nails 19 that pass through the struck out lugs 20 from said member. In addition, I provide the vertical struts 21 and horizontal braces 22, all of 95 which are of common construction.

100 By the use of the means described a metal frame may be installed and aligned with the minimum of labor and material and the real economy in the use of metal bucks is effected.

I claim:

1. In combination, vertical and horizontal buck members having overlapping portions at their junctions, a wood element mounted in a frame at the junction of said elements and extending vertically from said junction 110 and adapted to be secured to the ceiling.

2. The combination with the vertical and

horizontal metal members of a frame having overlapping portions at their junctions, of a wood member seated in the frame at said junction, fastening means passing through the overlapping portions into said wood member, said wood member extending vertically beyond the junction and adapted to be secured to the ceiling for holding the frame during the finishing of the wall.

10 3. In wall construction, the combination of a metal frame having overlapping portions at the junction of its members, a wood member mounted in the frame at said junction, fastening means extending through the metal members into the wood member, said wood member projecting upwardly to the ceiling and adapted to be secured thereto.

15 4. In combination, vertical and horizontal frame members of generally channel shape, one of said members having an angular end

projection adapted to cooperate with another frame member in overlapping relation, a wood block seated in the channel of a vertical frame member and projecting upwardly toward the ceiling and adapted to be secured thereto, and fastening means passing through the cooperating portions of the frame and into said wood member.

20 5. In combination, channel shaped frame members having overlapping portions, a wood block mounted in the channel of a vertical frame member, a thrust block or shelf serving as a lower support for said wood member, said wood member projecting upwardly beyond the frame and adapted to be secured to a ceiling.

25 30 In testimony whereof I have affixed my signature.

ISAAC A. BAUM.
